UNITED STATES PATENT OFFICE.

DENNIS F. FOX, OF CANDOR, NORTH CAROLINA.

VALVE.

1,069,541.

Specification of Letters Patent. Patented Aug. 5, 1913.

Application filed October 1, 1912. Serial No. 723,373.

To all whom it may concern:

Be it known that I, DENNIS F. FOX, a citizen of the United States, residing at Candor, in the State of North Carolina, have invented certain new and useful Improvements in Valves, of which the following is a specification, reference being had therein to the accompanying drawing.

This invention relates to engine valves and has for its object the production of an efficient engine valve of a rotary type which will use less steam and furnish more power for the engine.

Another object of this invention is the production of an efficient valve whereby the steam will be permitted to pass through the valve throughout the entire stroke of the piston and the exhaust will then be immediately relieved as soon as the piston has reached the end of the stroke whereupon the valve will be opened for driving the piston to its returned stroke.

Still another object of this invention is the production of a simple and efficient governor coöperating with the rotary valve which will automatically shut off the passage of steam through the valve when the speed of the engine has reached a predetermined point.

With these and other objects in view this invention consists of certain novel constructions, combinations and arrangements of parts as will be hereinafter fully described and claimed.

In the drawings: Figure 1 is a perspective view showing the engine with the valve and driving mechanism for the valve applied thereto. Fig. 2 is a front elevation of the governor used in connection with the valve. Fig. 3 is a view of the back of the valve seat. Fig. 4 is a section taken on line 4—4 of Fig. 2. Fig. 5 is a detail perspective of the valve and governor coöperating therewith. Fig. 6 is a detail perspective view of the inner face of the rotating valve.

By referring to the drawings by numerals it will be seen that 1 designates the base of the engine which carries the usual drive-shaft 2. A balance-wheel 3 is carried by the drive-shaft 2 and a belt-wheel 4 is carried

by the opposite end of the shaft 2. The usual piston connecting mechanism 5 is also carried by the shaft 2 for imparting rotary movement to the shaft through the medium of the piston-rod 6.

The cylinder 7 is carried near the front of the base 1 and a valve-casing 8 is carried upon the side of the cylinder which valve-casing supports a steam supply-pipe 9 upon its upper end and a steam discharge or exhaust-pipe 10 at its lower end. The valve-casing 8 is closed at its outer end by means of a plate 11, which plate 11 is held upon the casing 8 by means of bolts 12.

The valve-seat 13 which is formed upon the cylinder 7, is provided with a pair of substantially semi-circular openings 14 which constitute inlet-ports for admitting the steam to the valve into the respective ends of the cylinder 7. A partition 15 is formed between each end of the inlet-ports 14 and the exhaust opening 16 is formed centrally of the seat 13 for admitting the exhaust from the cylinder 7 to the exhaust-pipe 10. A brace member 17 passes transversely across the exhaust opening 16 and is provided with an enlarged bearing portion 18 through which the supporting shaft 19 of the valve 20 passes.

The rotary valve 20 is keyed to the supporting shaft 19 by means of a key 21 so as to cause the rotary valve 20 to rotate with the shaft 19. The rotating valve 20 is provided with an aperture 22 for allowing the passage of steam through said aperture into the inlet-ports 14 when the same comes in a position to register therewith. An exhaust receiving pocket 23 is formed upon the rear face of the rotating valve 20 and is substantially T-shaped, comprising an inlet passage-way 24 shown in dotted lines in Fig. 3, for permitting the passage of the exhaust steam from the ports 14 into the exhaust-ports 16. The inlet aperture 22 and the exhaust passage-way 23 are formed upon the valve 20 in diametrically opposite positions so as to allow the exhaust to be taken from one port as soon as the inlet aperture has been cut off from said port. The live steam is admitted into the compartment 24 which 100

compartment allows the passage of steam through the aperture 22, by means of an inlet passage-way 25, which passage-way communicates with the supply pipe 9. A discharge passage-way 26 is formed in the cylinder 7 and communicates with the outlet-port or exhaust-port 16 for conveying the exhaust steam from the port 16. This port 26 communicates with the discharge pipe 10. 5

10 A gear-wheel 27 is carried by the outer end of the shaft 19 and this bevel-gear 27 meshes with a bevel-gear 28 carried by the valve driving shaft 29. The shaft 19 is supported at its outer end by means of a bracket 15 30, which bracket is screwed to the outer plate 11. This outer plate 11 forms a closure for the compartment 24 which contains the rotating valve 20. A packing 32 is formed around the shaft 19 to constitute a steam 20 tight joint and prevent the passage of steam through the plate around the plate 19. This bracket 30 is adapted to hold shaft 19 against longitudinal movement. A bearing 33 is carried by the outer plate 11 and straddles 25 the shaft 29 adjacent the gear-wheel 28 and constitutes a support for said shaft. Bearings 34 are carried by the body of the engine and also support the shaft 29. A drive-gear 35 is carried by the rear end of the shaft 29 30 and meshes with the bevel-gear 36 carried by the main shaft 2. These gears are so arranged as to cause the rotation of the valve 20 in accordance with the stroke of the piston of the engine. 35

35 A closure arm 37 is pivotally secured to the rotating valve 20 by means of a pivot bolt 38 and this closure arm is provided with a weighted outer end 39 which weighted end will cause the outer end of the arm 37 to 40 swing outwardly when the speed of the valve 20 has reached a predetermined point, owing to the centrifugal force of the valve 20. This swinging movement of the arm 37 will close the inlet aperture 22 as will be seen 45 in dotted lines in Fig. 2, and thereby cut off the passage of steam into the cylinder of the engine. A guiding bridge 40 is carried by the valve 20 and the arm 37 works therethrough and it will be seen that this guiding 50 bridge will limit the swinging movement of the arm 37. A regulating lever 41 is pivotally secured upon the valve 20 by means of a pivot-pin 42 and a coil spring 43 connects the arms 37 with the free end of the lever 55 41 so as to normally hold the arm 37 away from the aperture 22. A journal 44 is formed upon the valve 20 and an adjusting screw 45 is threaded through this journal 44 and engages the rear end 46 of the lever 60 41. By means of this adjusting screw the lever 41 may be adjusted so as to regulate the tension of the spring 43 upon the arm 37.

From the foregoing description it will be seen that a very simple and efficient device

has been produced which will be at all times 65 shielded within the casing of the engine and which will automatically control the engine so as to shut the same off provided the engine should reach a speed above a predetermined point. It should also be understood 70 that by the use of the rotating valve as set forth, the cost of production and maintenance of the engine will be materially reduced over the engines and valves which are now placed upon the market. It should 75 be still further obvious that owing to the continuous open position of the inlet-port for supplying steam to the piston, the power of the engine will be greatly increased and that owing to the construction of the exhaust 80 pocket formed in the rotating valve, the exhaust steam will be readily and immediately withdrawn from the engine after the inlet-port has been closed. It should be still further obvious that owing to the driving mechanism for the rotating valve as set forth, the wear upon the engine will be materially reduced owing to the fact that by having the direct drive for the rotating valve as set forth, there would be no rattling of the parts 85 and hammering of the cams and eccentrics which usually takes place in the operation of the engine provided with the usual reciprocating steam valves.

From the foregoing description it will be 90 seen that as soon as the engine gets off-center, the steam will pass through the inlet-ports with full force so as to efficiently drive the piston.

What is claimed is:

1. An engine of the class described comprising a cylinder, a rotating valve carried by said cylinder, said rotating valve provided with an inlet aperture, a pivoted arm carried by said rotating valve, a weight 105 formed upon the outer end of said pivoted arm and adapted to swing outwardly for closing said arm over said inlet aperture, means controlling said arm for limiting the swinging movement thereof, a regulating 110 lever pivotally secured to said rotating valve, spring means connecting said arm with said lever, and an adjusting screw carried by said rotating valve and engaging said lever for regulating the tension of said spring 115 whereby said arm will be caused to swing over said inlet aperture at a predetermined point.

2. In an engine, a rotary valve provided with a port, an arm pivoted on said valve and arranged to swing over the port under the influence of centrifugal action, means to limit the movement of said arm, a spring connected with said arm and urging the same inwardly, and means connected with said 125 spring to regulate its tension.

3. In an engine, a rotary valve provided with a port, a member mounted on said valve

and arranged to move outwardly to cover the port under the influence of centrifugal force when the valve is rotated, means to limit the movement of the member, yield-
able means to resist the movement of the member, and an adjusting device for the last mentioned means.

In testimony whereof I hereunto affix my signature in presence of two witnesses.

DENNIS F. FOX.
